UNITED STATES PATENT OFFICE.

CHARLES H. SMITH, OF NEWFIELD, NEW JERSEY.

DESIGN FOR A TROWEL.

SPECIFICATION forming part of Design No. 26,204, dated October 20, 1896.

Application filed September 2, 1896. Serial No. 604,689. Term of patent 14 years.

To all whom it may concern:

Be it known that I, CHARLES H. SMITH, a citizen of the United States, residing at Newfield, in the county of Gloucester and State 5 of New Jersey, have invented a new and original Design for Trowels, of which the following is a specification.

This invention relates to a new and original design for trowels; and it has for its object to provide a design of this character that shall be both useful and ornamental.

The leading feature of the design resides in a trowel-body comprising a pair of duplicate flat rectangular oblong blades disposed at right angles to each other and convergently arranged, so as to merge into a common point at one edge, parallel V-shaped frames fitted against the blades in the angle therebetween, and a cylindrical handle disposed parallel 15 with the blades at a point intermediate of their opposite edges and carrying at its opposite ends inwardly-disposed parallel arm-pieces fitting in the angles of said V-shaped frames.

20 In the drawings, Figure 1 is a perspective view of a trowel embodying the herein-described design. Fig. 2 is a top plan view thereof.

The numeral 1 designates a trowel-body comprising a pair of duplicate flat rectangular oblong blades 2, disposed at right angles to each other and convergently arranged, so as to merge into a common point 3 at one edge. Parallel V-shaped frames 4 are fitted 30 against the inner sides of the blades and register with the angle therebetween, and a cylindrical handle 5 is disposed parallel with the blades at a point intermediate between the oppositely-located edges thereof. A pair of parallel arm-pieces 6 are projected inwardly, respectively, from opposite ends of the cylindrical handle and register at their 35 inner extremities, as at 7, in the angle of said V-shaped frames.

What is claimed is—

40 The design for a trowel herein shown and described.

In testimony that I claim the foregoing as my own I have hereto affixed my signature in the presence of two witnesses.

CHARLES H. SMITH.
